VACUUM CLEANER

Gustaf Einar Lofgren, Riverside, Conn., assignor
to Electrolux Corporation, New York, N. Y., a
corporation of New York

Application October 10, 1942, Serial No. 461,520

7 Claims. (Cl. 183—37)

This invention relates to improvements in vacuum cleaners. In particular, it relates to a vacuum cleaner of the type embodying a casing housing a motor-fan unit and a dirt separator which is adapted for connection to a flexible hose on the end of which a cleaning tool may be placed. When it is desired to clean in different parts of a room, the casing, which is mounted on wheels or runners, may be pulled around by the hose. The invention also relates to an improved device including a vacuum cleaner for discharging a mothproofing material into a garment bag.

One of the principal objects of the invention is to provide an improved disposition of the parts of a vacuum cleaner. Another object of the invention is to provide an improved arrangement of the parts of a combined vacuum cleaner and vaporizer. Other objects and advantages of the device will appear hereinafter as the description of the invention proceeds.

In the drawings, Fig. 1 is a side elevation of the vacuum cleaner showing the parts assembled for cleaning a floor. Fig. 2 is a side elevation of the vacuum cleaner showing the parts assembled for the vaporization of a mothproofing material and the discharge thereof into a garment bag. Figs. 3, 4, and 5 are front and rear elevations and a top view respectively. Fig. 6 is an elevation of the vacuum cleaner mostly in section. Fig. 7 is a sectional view in elevation of the motor-fan and fine particle filter unit. Fig. 8 is a bottom view partly in section of the last mentioned unit. Fig. 9 is a sectional view taken on the line 9—9 of Fig. 8. Fig. 10 is a sectional view on an enlarged scale of the junction between the unit and the rest of the vacuum cleaner. Fig. 11 is a section taken on the line 11—11 of Fig. 6. Fig. 12 is a section taken on the line 12—12 of Fig. 11, but with the elements 51 and 52 in overlapping closed position. Fig. 13 is a sectional view through the dirt drawer of the vacuum cleaner, showing the latching mechanism therefor.

Referring to Fig. 1, there is shown a hollow casing 2 for the main portion of the vacuum cleaner designated generally by the reference character 1. A flexible hose 3 is connected to an opening 5 in the casing 2 and may be disengaged therefrom by means of the latch 79. The other end of the hose is provided with a combination handle and tool-connector 6 which is shown to be in the shape of an elbow to facilitate the use of a tool connected thereto. A suction cleaning tool 7 may be directly connected to the handle 6 or an extension tube 8 may be in-

serted therebetween. At the bottom of the casing 2 there is a sliding dirt drawer 10 having a latching mechanism controlled by handle 18. The latching mechanism engages catch means in the wall of the casing shown at 64. The casing 2 is supported on runners 11 which space the bottom of the casing from a flat supporting surface and permit the casing to be easily pulled over the surface. The casing may be lifted and carried by means of a handle 12 pivoted at 13. There is an electric plug connector 14 to which an electric cord from a suitable power supply may be connected. A switch 15 controls the completion of the electric circuit to the electric motor inside of the cleaner. A unit 16 containing all of the moving parts of the cleaner is inserted through an opening in the top of the casing 2 and is held in place by manual latch means 17. There is an opening 19 in the top of the casing 20 at one side thereof leading into a pocket or compartment 69 of the casing which may be used either for carrying cleaning tools or for supporting a vaporizable substance used in mothproofing, as is indicated at 65 in Fig. 2. There 25 is an opening 21 in the side of the casing 2 leading into the pocket. As shown in Fig. 5, there is a perforated plate 20 near the bottom of the pocket separating the opening 19 from the opening 21. There is an exhaust opening 9 in the top 30 of the unit 16.

In Fig. 2 there is shown the apparatus set up for use in connection with a garment bag for producing rapid vaporization of a mothproofing material into the air inside of the bag. The garment bag 49 has an opening in the bottom thereof at 48 which is slipped over the top of the vacuum cleaner. This opening may have a draw string or an elastic band or other means for making a tight connection with the sides of the casing 2. The cleaning tool 7 has been disconnected from the connector 6 and the connector 6 has been inserted in the opening 21 so that air entering the vacuum cleaner must enter through the opening 19 and pass over the vaporizable material 65. After passing over the vaporizable mothproofing material 65, the air enters the connector 6 and flows through the hose 3 into the inlet opening 5 in the casing 2. The motor-fan unit inside of the casing draws the air into the casing 2 and exhausts it through the opening 9 into the interior of the garment bag 49. Since all air entering the cleaner comes from within the garment bag, it is seen that a recirculating system is provided by means of which the air in the garment bag, which is quickly heated from

the heat of the motor-fan unit, is continuously passed over the mothproofing material 65 and thus quickly vaporizes the material 65 to produce a high concentration of the mothproofing material within the bag 49.

Figs. 6, 7, and 8 show the interior construction of the vacuum cleaner. A semi-permeable fabric 22 formed of finely woven cloth or similar material is supported from a ring 23 having an outwardly extending flange 66 which is supported on the top of the casing 2 and which may be connected thereto by a suitable fastening means designated by the reference character 50 (see Fig. 10). The ring 23 and the fabric 22 need be removed only on those infrequent occasions when it is necessary to replace the fabric.

The semi-permeable fabric 22 divides the casing 2 into an upper and lower chamber, the fabric 22 being formed generally into the shape of a bag or cup. Within the upper chamber the unit 16 is mounted. The unit 16 rests upon the flange 66 to which the fabric 22 is connected. A rubber gasket 24 (see Fig. 10) may be provided to form a tight seal between the unit 16 and the flange 66. The unit 16 contains a motor 25, the housing of which is connected, as at 28, by means of bolts and a gasket, in airtight relationship with the casing 27 of a two stage fan 26. The motor 25 is preferably a series motor adapted to be operated either from alternating or direct current. The casing 27 is provided with a tubular opening 31, by means of which the fan end of the motor-fan unit is resiliently supported in bulkhead 33 on a rubber ring 29. The ring has slots 30 cut therein to improve the vibration deadening qualities thereof. The bearing at the commutator end of the motor-fan unit is resiliently supported in bulkhead 33 by means of a rubber ring 35 having slots 35a cut therein adjacent to its outer periphery. Depending from the bulkhead 33 radially inwardly of the perforated outer portion thereof is a cup shaped member 80, the lower edge of which is below the opening in the commutator end of the motor frame. The purpose of member 80 is to deflect air flowing out through these openings and to thereby reduce the volume of motor and fan noises which are carried by the air stream. The bulkhead 33 has perforations 37 therein.

The bottom of the casing 34 surrounding the motor-fan unit is open and a wire screen or other foraminous member 43 is supported therein within a rolled bead 67. The screen protects the motor-fan unit against the entrance of pins and needles, etc., should it be operated separately from the rest of the cleaner. Against the screen 43 there is placed a pad 45 of matted or felted fibres which serves as a fine particle filter to remove from the air tiny particles which pass through the semi-permeable fabric 22. The pad 45 preferably is made up of a layer of cotton padding and a layer of carded cotton enclosed between two layers of napped flannel. The fine particle filter is held in place by means of a cover 38 which fits over the end of the casing 34 and is held thereto by means of knurled nuts 39 which engage studded bolts on the casing 34. The cover 38 has an inwardly dished portion 40 which contacts the center of the fine particle filter 45. There are apertures 41 in the sides of the cover 38 and apertures 42 in the bottom thereof.

As best shown in Figs. 6, 8 and 9, there are perforated members 46 and 47 comprising a number of flanged plates spaced around the outer

periphery of the casing 34 and the cover 38, respectively. These perforated plates space the semi-permeable fabric 22 from the casing 34 and cover 38 and provide channels 44 for the flow of air down the sides of the casing 34 and into the openings in the sides of the cover 38. The general path of the flow of air is indicated in Fig. 9 by arrows.

Referring now to Figs. 11 through 13, there is shown the construction of the dirt drawer 10. At one end of the dirt drawer there are swinging doors 51 and 52 pivoted at 53 and 54, respectively. When the drawer is removed from the vacuum cleaner, the springs 55 and 56 force the doors into a position to close the end of the drawer. When the drawer is inserted into the cleaner, however, the tube 4 for coupling the air conduit penetrates within the drawer and opens the doors 51 and 52. The springs 53 and 56 are normally not sufficiently strong to force the drawer out of the cleaner against the friction caused by the weight of the drawer. In any case, however, the drawer will be held in place in the cleaner by means of latches 63 which engage recesses formed in the casing as at 64 (see Fig. 1). Fig. 13 shows the arrangement of the latching mechanism. On the end of the handle 18 there are crown gear sectors 57 (see also Fig. 6). The handle 18 is pivoted at 58 to the end of the drawer 10 and has fixed thereto crown gear sectors 51 which engage spur gears 59 which in turn engage spur gear sectors 60. The spur gear sectors 60 also include cam faces 61 which are held in contact with cam follower rollers 68 on latch member 63 by means of springs 62. It can be seen from the drawings that when the handle 18 is pulled outwardly, the cam 61 is operated in a direction to permit the retraction of the latch member 63, thereby permitting the drawer to be withdrawn by a motion of the handle 18 in the same direction as the drawer moves when it is withdrawn.

Having now described the general construction of the combined vacuum cleaner and vaporizer, its use and operation may be briefly outlined. With the hose 3 connected to the opening 5 of the vacuum cleaner and the connector 6 coupled to a cleaning tool, as shown in Fig. 1, the apparatus may be operated as an ordinary vacuum cleaner. Air will be drawn in through the cleaning tool 1 and conduit 3 into the opening 5 and thence through the semi-permeable fabric 22 into the unit 16. When the air enters the drawer 10 its velocity is decreased and its direction is changed so that heavy dirt and dust particles entering with the air will be thrown toward the far side of the drawer and will settle to the bottom. Smaller particles which are not thus caught will be stopped by the semi-permeable fabric 22 and will either be caught thereon or will fall into the dirt drawer 10. Microscopic particles of material which may pass through the semi-permeable fabric will be carried with the air to the openings in the bottom of the unit 16. In order to enter the interior of the unit 16, they must first pass through the long small tortuous passages between the matted fibres of the fine particle filter. Because of the curves in these passages, the particles will be thrown against the fibres of the pad and will largely be retained thereby. The air carrying these particles, however, will pass on through the fine particle filter and into the motor-fan unit. As the air passes by the motor it serves to cool same. Air leaves the motor after passing over the commutator and

out through openings in the end cap and finally passes around the rubber sound deadening member 80 through openings 37 in the bulkhead 33 and out the exhaust port 9.

Continued operation of the cleaner will cause dirt to accumulate in the dirt drawer and on the semi-permeable fabric. To maintain maximum cleaner efficiency the fabric should be shaken to free it from particles of dirt caught thereon and the dirt drawer should be emptied after each use of the cleaner. The fabric should be shaken while the drawer is in place so that the dirt falling therefrom can be removed with that already in the drawer. To get at the fabric the latches 17 are unfastened and the unit 16 removed. The fabric can then be turned inside out and shaken into the drawer. To remove the drawer it is necessary only to pull on its handle which automatically unlatches it. After the drawer is emptied and replaced, pressure on the handle in shoving the drawer home automatically latches it in place.

It is only after protracted operation of the cleaner that the passages of the fine particle filter becomes sufficiently clogged to impair the efficiency of the machine. When this does happen the unit 16 is removed from the cleaner casing and the thumb screws 39 are unscrewed so that the cover 38 may be taken off. The fine particle filter is then removed and replaced and the machine may again be assembled for use.

If it is desired to use the vacuum cleaner to operate a blowing device such as a sprayer, the hose 3 may be disconnected from the opening 5 and connected to the opening 9. The sprayer or other blower device may be connected to the connector 6. When the push button switch 15 is operated to close the circuit to the electric motor, the fan 26 will draw air in through the opening 5 and over the path previously described and out through the opening 9 into the conduit 3 to operate the blowing device.

If it is desired to use the vacuum cleaner as a vaporizer for a mothproofer or other air conditioning material, the connector 6 of the hose 3 may be inserted into the opening 21 and the other end of the hose connected either to opening 5 or opening 9. Operation of the motor-fan unit will then cause air either to be drawn in or blown out through the opening 19 and in either case, it will pass over the air conditioning material resting on the perforated plate 20. If the vacuum cleaner is connected so that air is drawn into the opening 19, a flaked or granulated material may be used in the pocket 69. However, if the cleaner is connected so as to blow air out through the opening 19, it would be preferable to use a solid cake of material within the pocket 69 or else to enclose the flakes within a porous container. When used as a vaporizer, the vacuum cleaner can be connected to a garment bag as shown in Fig. 2 or it can be placed within a closed closet. In either case, the vacuum cleaner serves to rapidly vaporize a mothproofer or other air conditioning agent and to saturate the air in the garment bag or the closet with the vapor. The vacuum cleaner may also be connected as just described and placed in an open room to purify the air therein by removing pollen, dust, and microscopic organisms floating therein and to kill bacteria therein. When the cleaner is thus used as an air-conditioner, the pocket 69 may be filled with some material which has a germicidal action and also preferably which has a pleasant

odor. In such case, or in any case, the fine particle filter 45 may also be impregnated with a germicide similar to that placed in the pocket 69.

It will thus be seen that there has been provided by this invention a novel structure forming a combined vacuum cleaner, blower, and vaporizer. It is to be noted that those elements which need attention most often are readily accessible while those parts which need rarely be touched are so mounted as to be out of the way where they will not unnecessarily be disturbed. While one preferred embodiment of the invention has been described, it is obvious that many modifications therein may be made without departing from the invention. For example, other forms of coupling means than those shown might be used in the openings 5, 9 and 21. The dirt drawer 10 might be formed with no end wall thereby eliminating the necessity for the doors 51 and 52. A variety of other forms of latching means might be substituted for that connected to the handle 18. The cleaner might be supported on wheels instead of the runners 11. The spacing members 46 and 47 might be formed as a separate unit removable from the cleaner separately from the unit 16 or they might be formed as a single perforated cylinder bolted to the top of the unit 16. The motor-fan unit might be resiliently supported in a single central plane instead of by means of the two bulkheads 33 and 36. It is intended to protect by these Letters Patent all forms of the invention falling within the scope of the appended claims.

What I claim is:

1. A vacuum cleaner comprising a first hollow casing having a first opening near the bottom thereof and a second opening near the top thereof, a bag shaped semi-permeable fabric supported in said casing with a mouth of the bag coincident and adjacent said second opening, said fabric separating said casing into upper and lower chambers, the lower chamber constituting a dirt collector, a unit in the upper chamber supported from the casing adjacent said second opening and extending within said bag, said unit comprising a second hollow casing having openings in the bottom and top thereof and otherwise closed, electric means within the second casing for producing a flow of air therethrough, a fine particle filter so disposed within the second casing that all air flowing through the second casing must pass through the fine particle filter, an electric cord connector for connecting said electric means to a source of power, and an electric switch for controlling said electric means, said connector and switch being mounted on said second casing at the top thereof, said unit including said fine particle filter being removable through said second opening.
2. A vacuum cleaner comprising a hollow casing divided by a semi-permeable fabric into two chambers, said fabric having a cup shaped portion with its mouth adjacent an opening in one of the chambers of the casing, and a unit insertable through said opening into said cup shaped portion, means for removably securing said unit in place, said unit comprising a hollow casing having apertures at opposite ends thereof, a direct coupled motor-fan assembly resiliently supported therein, a foraminous wall separating one of the apertures from the assembly, a fine particle filter supported against air flow by said foraminous member so disposed that the air flowing through the unit passes through the pad,

an electric connector, and wires connecting the motor with said connector, whereby said unit including said filter and electric connector is removable as an integral unit from said casing.

3. A vacuum cleaner comprising a housing divided by a semi-permeable fabric into two chambers and a unit insertable through an opening in said housing into one of said chambers, means for removably securing said unit in place, said unit comprising a hollow casing having apertures at opposite ends thereof, a direct coupled motor-fan assembly resiliently supported therein, a fine particle filter supported therein in such a position that air flowing through said casing must pass through the pad, an electric connector mounted on the casing, and wires connecting the connector to the motor, whereby said unit including said filter and electric connector is removable as an integral unit from said casing.

4. In a vacuum cleaner, a casing formed with an inlet opening and a second opening, a bag shaped dust separating member having an open mouth permanently fixed in sealing relation to said casing around said second opening and normally extending into said casing, a motor-fan unit removably secured to said casing around said second opening and extending into said casing within said dust separating member, said unit including an imperforate cylindrical casing, constituting the exterior portion, a perforated rigid structure secured in spaced relationship to the exterior portion of said unit which is within said dust separating member for spacing the latter from said unit, said unit having an air inlet within said dust separating member and an exhaust opening outside said casing.

5. In a vacuum cleaner, a casing formed with an inlet opening and a second opening, said second opening being in an upper substantially horizontal wall of said casing, a bag shaped dust separating member having an open mouth fixed

to said casing around said second opening and normally depending into said casing, a motor-fan unit removably secured to said casing around said second opening and extending into said casing within said dust separating member, said unit including an imperforate cylindrical casing having an air inlet within said dust separating member and an exhaust opening outside said casing, and a removable dust receiving receptacle normally positioned below said dust separating member.

6. A vacuum cleaner comprising a hollow casing, a dust separating screen within said casing, a hose coupling in the lower portion thereof, extending inwardly from an opening in said lower portion, a dirt receptacle removably mounted in said lower portion and removable through a second opening thereof, said receptacle having an aperture in one side thereof through which said hose coupling extends when said receptacle is seated within said casing and means for automatically closing said aperture as an incident to removal of said receptacle from said casing.

7. A vacuum cleaner comprising a hollow casing, a dust separating screen within said casing, a hose coupling in the lower portion thereof, extending inwardly from an opening in said lower portion, a dirt receptacle removably mounted in said lower portion and removable through a second opening thereof, said receptacle having an aperture in one side through which the hose coupling extends, closure means for said aperture operable to open position by contact with said coupling, spring means automatically closing said aperture on removal of said receptacle, said spring means being too weak to cause movement of said receptacle due to the pressure exerted thereon after the reception through said opening of said hose coupling.
